FACING BLOCK SECURED TO A CONCRETE WALL

William H. Krueger, Milwaukee, Wis., assignor, by direct and mesne assignments, to Building Equipment Patents Company, Milwaukee, Wis., a corporation of Wisconsin

Application January 27, 1943, Serial No. 473,734

2 Claims. (Cl. 72—19)

1

The main object of this invention is to provide for facing concrete walls of the type embodying tie rods comprehended by my former Patent No. 2,297,899, dated October 6, 1942.

Another object of the invention is to provide facing tiles with sockets for receiving the end of the tie rods, which sockets cooperate with a locking key seated in the key slot of the tie rod extremity.

A still further object of the invention is to provide a facing tile for concrete or other prefabricated walls, which will be extremely cheap in production and easy to manufacture, and which will be formed of a material available commercially and capable of desirable ornamental effects or designs suitable for utilization in a multiplicity of building situations where wall finish may be subject to administrative as well as artistic limitation.

The invention obviously comprehends the joining of the top, bottom or end faces of tile blocks, with respective top, bottom or end faces of similar blocks, so that one or more tie rods 2 with its or their anchoring keys shall equally bear each adjacent face of a block.

Reference will be had to the accompanying drawings forming a part of this specification and wherein like characters of reference designate corresponding parts throughout the several views, in which,

Fig. 1 is a vertical sectional view through a wall embodying the application of a finishing tile prior to its movement into locked position.

Fig. 2 is a fragmentary front elevation showing the application of the invention as in Figure 1.

Fig. 3 is a section on line 3—3 of Fig. 1.

Fig. 4 is a section taken on line 4—4 of Fig. 1.

Fig. 5 is a view similar to Fig. 1 in which the tile has been moved to its locked position.

Fig. 6 is a front fragmentary elevation of Fig. 5.

Fig. 7 is a longitudinal section taken through the tile at a point in the structure of line 4—4 of Fig. 1 but including a super-imposed tile in locked position.

Fig. 8 is a side elevation of the anchoring key, and

Fig. 9 is an end view of the anchoring key.

In illustrating the present invention I have shown a concrete wall 1 cast in accordance with my prior Patent No. 2,297,899, dated October 6, 1942, to include cross ties 2 which are spaced at regular intervals and in accordance with predetermined design and requirement to accommodate facing tiles of different sizes as hereinafter described. The face tiles may include a backing

or body 3 of suitable aggregate and a facing 4 of predetermined design or the entire tile unit may be molded or formed as an integral mass of identical aggregate. The type of facing tile used 5 can be varied in accordance with the wishes of a builder or contractor, it being merely essential that these facing tiles include a body of such dimension as to permit the formation of sockets of predetermined design for locking engagement 10 with the extremity of the tie member 2 and the locking key 5. In the illustration the wall 1 is shown as formed with a shelf 6 for supporting engagement with the lower face 7 of the bottom row of tiles which are to be attached thereto.

15 It will be noted that the tie members 2 extend a suitable distance beyond the side face of the wall and are provided in the present instance with vertically formed key slots. Each key slot includes the enlarged central portion 8 and the reduced end portions 9 and 10 and the shape of these key slots is such as to cooperate with the anchoring keys 5 shown in detail in Figs. 8 and 9.

20 The anchoring key 5 is of elongated rectangular shape and generally square in cross section 25 with its dimensions such as to permit it passing lengthwise through the enlarged central portion 8 of the key way in the end of the tie rod 2. Intermediate its length and at its front and rear walls the anchoring key 5 is formed with vertical 30 grooves 12, the width and depth of which are such as to allow the same reciprocable cooperation with and travel upon the parallel edges at the reduced ends of the key slots in the tie rod. By this construction the key 5 can be inserted approximately half its length through the enlarged 35 portion 8 of the key way in the end of the tie rod 2 and moved vertically to each side of the enlarged portion 8 to embrace the adjacent walls forming the reduced portions 9 of the key way. Thus the anchoring key 5 may be dropped into 40 position upon the bottom of the key way in the end of the tie rods 2 and held against lateral movement upon positioning of the block on the tie rod as will more clearly hereinafter appear.

The body of the tile 3, while being molded, is formed with a cavity shaped to provide a socket portion 14 to receive the end of the tie rod 2 and a socket portion 15 to receive the key 5 associated therewith and to permit these parts to be moved horizontally and vertically with relation to the facing block during the positioning and anchoring of the tile. This relative movement is obviously brought about by the shifting of the facing block during the seating movement on the tie rod 45 and is essential in bringing about a locking of the

various parts in accordance with the purpose of the invention.

In general the blocks 3-4, will be constructed to lock with each end of each tie rod 2 in pairs, i. e., the end of the tie rod 2 and the anchoring key 5 are constructed and arranged to cooperate with an lock an adjacent pair of facing blocks or tiles by cooperation with their companion sockets. In view of this fact the construction of the blocks 3-4 which are to be assembled with the tie rod 2 in pairs will first be described. In this type of block the locking socket which is molded to receive the end of the tie rod and the anchoring key is formed along one side of the block, the formation being preferably at each side of each block and intermediate the length of the abutting side walls of the blocks and in a manner so that the sockets of each adjacent side wall will cooperate to form an anchoring means for each tie rod end. This is accomplished by the socket in the side wall of each block being constructed of sufficient dimension to accommodate only one-half of the tie rod and one-half of the anchoring key and in this manner two blocks will cooperate to lock each other to a single tie rod when the blocks are arranged in their predetermined relation.

The locking socket can be provided at each end of each tile or block or/and at the top and bottom of each tile or block, such arrangements as previously stated being of half dimension with respect to the tie rod 2 and the anchoring key 5 and cooperating with a similar structure of the adjacent tile or block. In Fig. 1 such a block is illustrated with the cavity or recess 14 formed in its side face and of greater width than the width of the tie rod 2 to permit relative movement of the latter in the locking of the block by shifting of the block as will be hereinafter further described. The recess 14 is of a depth approximating one-half the thickness of the tie rod which seats therein. It will be noted that the block is of such thickness that the end of the tie rod 2 does not extend through the wall but stops inwardly of the outer wall face to avoid weakening the structure at this point. Formed in the block and suitably arranged within the confines of the recess 14 is an L-shaped slot, the shank 15 of which extends horizontally from the inner face inwardly within the block, with the foot portion of the L extending vertically and substantially parallel with the outer face of the block. The dimension of this L-shaped slot is such to accommodate one-half of the protruding portion of the anchoring key 5, and to permit movement of this key within the slot during positioning and locking of the block 3 by inward and vertical movement. The foot 16 of the L-shaped slot is so formed and arranged that a vertical center line extending medially of the key body 10 will also extend medially of the key slot in the tie rod 2.

Needless to say that the sockets in the event that the tie rods are arranged horizontally rather than vertically as in the present illustration, may be formed in the upper and lower surfaces of the tile block, in which instance the construction and application of the block would be identical with that at present illustrated except that both of the movements for locking the parts will be in a horizontal plane rather than horizontally and vertically as in the present illustration.

In applying blocks to the wall it will be advisable to start at the bottom so that the lower blocks will in their seated position engage and

rest upon the shoulder 6 extending from the wall 1. The blocks in pairs will be inserted on the extending portions of the tie rod 2 with the latter engaging the lower face of the companion slots formed in the adjacent walls of the blocks. The insertion of the facing blocks on the tie rod will result in a relative arrangement of parts as indicated in Figs. 1 and 2 and when in this position the blocks will be lowered to engage with shoulder 6, which lowering will result in the upper portions 15 of the sockets seating over the ends of the anchoring keys as shown in Figure 6.

By means of proper removable cores, in the molding of the tie blocks or facing members, any combination of cavities may be provided for attaching a single block or a combination of blocks to a single tie rod or a combination of tie rods. In Fig. 7 a view is shown, corresponding to Fig. 4, in which the upper tile is positioned above a lower tile, the two tile structures forming the complete socket for the reception of the tie rod and the key. In substantially all instances the invention will be used as shown, i. e. with half of the locking recesses formed in each of two abutting faces of two adjacent tiles, with the recesses properly registering to receive the tie rod and key.

Where it is intended that the finishing blocks or tile are to become a permanent part of the concrete wall, it will be apparent to one skilled in the art that in this instance a suitable cement will be placed within the cavities receiving the tie rod extremities and anchoring keys so that when the cement is hardened the blocks will be fixedly secured thereto. This, of course, may apply in instances where the cavities are formed partially on adjacent portions of adjacent faces of the blocks or where the cavity is to be formed entirely in a single block. The usual method of applying a cement between the blocks or between the blocks and the concrete wall may also be utilized although with the present locking arrangement it may be unnecessary to add to the locking means furnished by the present invention.

I claim:

1. In combination with a concrete wall having a tie rod fixedly imbedded therein with its end portion projecting therefrom, said tie rod having a laterally extending, transversely slidable projection at its free end, a facing block, said facing block being formed with a first recess extending outwardly from its inner face and receiving the end of the tie rod, said recess being of greater diameter than the width of said tie rod, providing for relative movement between the tie rod and facing block in the direction of the width of the tie rod when assembled, and an L-shaped recess in the bottom of the first recess having one leg extending outwardly from the inner face of the block and its other leg extending parallel to and spaced from the inner face of the block whereby said removable projection is initially inserted into the first leg of the L-shaped recess and then upon shifting of the block relative to the tie rod is finally seated into locking position in the second leg.

2. In combination with a concrete wall having a tie rod fixedly imbedded therein with its end portion projecting therefrom, said tie rod being formed with a transverse slot adjacent its free end and said slot having an enlarged medial portion, a transversely slidable key arranged in said slot, said key being formed with transverse grooves in its outer face receiving the walls defining the slot, a facing block, said facing block

being formed with a first recess extending outwardly from its inner face and receiving the end of the tie rod, said recess being of greater diameter than the width of said tie rod providing for relative movement between the tie rod and facing block in the direction of the width of the tie rod when assembled, and an L-shaped recess in the bottom of the first recess having one leg extending outwardly from the inner face of the block and its other leg extending parallel to and spaced from the inner face of the block, whereby said key is initially inserted into the first leg of the L-shaped recess and then upon shifting of the block relative to the tie rod is finally seated into locking position in the second leg.
